UNITED STATES PATENT OFFICE

154,376

DESIGN FOR A CIGAR LIGHTER OR
SIMILAR ARTICLE

Alexander L. Flamm, Bridgeport, Conn., assignor
to Ronson Art Metal Works, Inc., Newark, N. J.,
a corporation of New Jersey

Application February 19, 1949, Serial No. 955

Term of patent 14 years

(Cl. D48—27)

To all whom it may concern:

Be it known that I, Alexander L. Flamm, a citizen of the United States, residing at Bridgeport, in the county of Fairfield and State of Connecticut, have invented a new, original, and ornamental Design for Cigar Lighter or Similar Article, of which the following is a specification, reference being had to the accompanying drawing, forming part thereof in which,

Fig. 1 is a side elevational view of a cigar lighter or similar article, showing my new design.

Fig. 2 is a top plan view thereof.

I claim:

The ornamental design for a cigar lighter or similar article, substantially as shown.

ALEXANDER L. FLAMM.
